The ornamental design for a pet water fountain, as shown and described.

DESCRIPTION

FIG. 1 is a perspective view of a pet water fountain.

FIG. 2 is a front view thereof.

FIG. 3 is a rear view thereof.

FIG. 4 is a left view thereof.

FIG. 5 is a right view thereof.

FIG. 6 is a top view thereof; and,

FIG. 7 is a bottom view thereof.

The evenly spaced broken lines depict portions of the pet water fountain that form no part of the claimed design. In FIGS. 1 and 6 the dot dash dot broken lines denote the boundaries of the claimed areas and form no part of the claimed design.
